UNITED STATES PATENT OFFICE

JOSEPH ZUBATY, OF FLINT, MICHIGAN, ASSIGNOR TO A C SPARK PLUG COMPANY, OF FLINT, MICHIGAN, A COMPANY OF MICHIGAN

MOUNTING OF SPEED CUP AND ROTOR SHAFT

Application filed March 11, 1926. Serial No. 94,096.

This invention relates to measuring instruments. It is particularly concerned with an improved speedometer, but its novel construction will be found useful in other instruments as well.

Among the objects of the invention are an improvement in the mounting of the magnet for a magnetic speedometer, an improvement in the mounting of a rotor shaft, and an improvement in the speed cup mounting. Other objects will appear as the full description proceeds.

In the drawings:

Figure 1 is a top plan view of the frame and parts of the speedometer, the casing having been removed. Figure 2 is a vertical section on line 2-2 of Figure 1. Figure 3 is a rear elevation of the lower part of the instrument. Figure 4 is a section on line 4-4 of Figure 3. Figure 5 is a detail showing in section the lower bearing of a speed cup spindle.

Referring by reference characters to the drawings, numeral 1 represents a frame member carrying the speedometer and odometer parts. This frame is a die casting and is of a somewhat box shape. At the right of Figure 2 will be seen the annular resilient plate 3 which is fastened to the frame and which 25 furnishes the sole connection between the instrument and its casing. It is intended that this resilient plate 3 shall take the shocks and jars from the vehicle instrument board and absorb them before they are transmitted 30 to the delicate parts of the instrument.

The magnet 5 is of a well known U shape. It engages the frame at three points. The lower point of contact with the frame is shown in Figure 2 at 7 and the two upper 40 points at 9 as in Figures 1 and 4. For securing this magnet to the frame a relatively long channel bar 11 is used. This bar 11 is centrally secured to the frame by machine screw 13. One of the walls of the channel bar near 45 each end is cut away as shown at 15 in Figure 4 thus enabling the channel bar to conform to the angularity of the magnet. It will be seen also from Figure 4 by the dotted lines that the channel member overhangs the outer 50 sides of the magnet.

Substantially in the center of the frame is a vertical passageway through which passes the rotor shaft 17. The upper end of the rotor shaft is turned over to secure rigidly thereto the rotor proper 19 and just beneath the rotor the shaft is formed with a worm 21. This worm 21 engages the worm gear 22 on the so-called second worm shaft. It will be seen that in assembling the parts, the rotor or first worm shaft with the rotor is pushed down through the vertical passageway in the frame and brought into geared engagement with the second worm shaft. For the purpose of holding the shaft 17 in position use is made of a clip 23. This clip is of U shape, its upper arm engaging a shoulder 26 on the shaft 17 and its lower arm engaging the frame member. To prevent this clip slipping off the frame and releasing its hold on shaft 17, the magnet holding bar 11 is made use of. From Figure 2 it will be seen that the central portion of this magnet holding bar projects upwards sufficiently to prevent the clip 23 from slipping off the frame and releasing the shaft 17, an oiling wick 70 may be placed in the space under the screw 13 to lubricate shaft 17.

The speed indicating member of the speedometer, or the speed cup, so-called, is mounted by means of clamps 25 on the spindle 27. Differing from the common construction of mounting the lower spindle bearing in a frame member, I prefer to utilize the rotor shaft 17 for carrying the lower bearing. It will be seen from Figure 2 and better still from Figure 5 that the upper end of the rotor shaft 17 is provided with a shouldered recess 29. Into this recess is inserted a jewel carrier 31. In the bottom of the jewel carrier is a jewel 33, the upper surface of which is finished to furnish a bearing for the end of the spindle 27. The metal of the cup is crimped under the jewel as at 35 to hold the jewel in position. Above the jewel 33 and engaging a shoulder in the cup 31 is a hole jewel 37. For the purpose of holding this hole jewel in position the metal may be shaved into engagement therewith. Over the speed cup and secured to the upper portion of the frame is a somewhat U shaped 100

plate 39, screws 41 being shown to secure the plate to the frame. The plate is provided with an opening in alignment with the recess at the upper end of the rotor shaft 17 and in this opening is inserted a shouldered jewel carrier 43. Mounted in the jewel carrier 43 is a hole jewel 45, the metal of the carrier being shaved down to hold the jewel in position as before. Surrounding the circular 10 upper portion of the carrier, which it will be observed lies above the plate 39, is the apertured split pivot portion of a lever 47.

This lever extends forward as at 49 to a point convenient for operation. It extends 15 to the rear and has a downward extremity 51 to which is connected the end of hair spring 53, the other end of the hair spring being connected to the spindle 27 as usual.

Means is provided to limit the rotation of 20 the speed cup as influenced by the hair spring at a point where the zero reading shall be in proper position. For this purpose an angle lever 55 is pivoted near the front of the plate 39. The lower portion of the angle 25 member 55 projects downwardly where it engages a lug 57 projecting upwardly from the speed cup. The purpose of the pivotal connection of lever 55 is to provide a correction for slight inaccuracies in manufacture and 30 assembly. A second lug 59 is also provided on the speed cup to limit the rotation of the speed cup to somewhat less than three hundred sixty degrees (360°). The purpose of 35 this second lug is to prevent the reading of the indicator returning to zero after the speed of the vehicle exceeds the maximum reading in miles or kilometers per hour, as indicated by the speed cup.

For retaining the spindle 27 from axial 40 movement and for holding the spring adjusting lever 47 firmly against the plate 39 I prefer to use a U shaped resilient member 61. One arm of this U shaped member lies a few thousandths of an inch above the end of the 45 spindle 27. The other arm of the U shape member is forked and engages lever 47 adjacent its pivot. A screw 63 passes through the upper arm of the U shaped member and is extended into the frame member. By 50 means of this screw the tension of the U shaped spring upon the lever 47 is made variable as also is the clearance at the upper end of the spindle 47.

The odometer mechanism is not per se a 55 part of this invention. It includes vehicle wheels, one of which is designated by numeral 60. These wheels may be driven by any suitable driving means (not shown) from shaft 22. The shafts for the odometer 60 wheels as at 62 will be mounted in the end walls of the frame in the usual way. It will therefore be seen that the odometer mechanism may be conveniently arranged on one side of the intermediate part of the die-cast frame which carries rotor shaft 17 and that

the fixed U-shaped magnet is clamped to the opposite side.

I claim:

1. In a magnetic measuring instrument, a frame, a rotor shaft therein, a magnet, holding means therefor, a clip for retaining the rotor shaft, the magnet holder positioned to prevent the escape of the retaining clip. 70

2. A measuring instrument, a rotary indicating member, a frame member thereover, the frame member having a jewel carrier mounted therein for the spindle of the indicating member, the carrier extending slightly above the frame, a hair spring adjusting lever journalled about the projection of the jewel carrier, a U-shaped resilient member, one arm retaining the spindle from axial movement and the other arm engaging the lever to hold it in adjusted position. 75

In testimony whereof I affix my signature. 80
JOSEPH ZUBATY.
